UNITED STATES PATENT OFFICE

2,673,634

TERMINAL LINK FOR FLEXIBLE FEED CHUTES

Robert L. Corbo, Van Nuys, Calif., assignor to
 Hughes Tool Company, Houston, Tex., a corporation of Delaware

Application October 24, 1950, Serial No. 191,799

2 Claims. (Cl. 193—25)

1

This invention relates to improvements in terminal links for flexible feed chutes, and more particularly to improvements in terminal links including members for connecting the ends of such feed chutes to apparatus for receiving and discharging rounds of ammunition, e. g., ammunition boxes, ammunition booster mechanisms and loaders, automatic guns, etc., such as disclosed in the U. S. Patents 2,477,264 and 2,419,315.

When a flexible feed chute is connected between an automatic gun and an ammunition box to provide a passageway for guiding ammunition assembled in belt formation, the general practice has been to provide terminal links for the ends of the chute having fixed connectors projecting from surfaces or edges of the links for engagement with suitable companion members located on the gun and the ammunition box or any other apparatus to which the chute is connected. In connecting or disconnecting such links, considerable movement of the chute away from the place of attachment is required in order to remove the connectors from their companion members. Moreover, the process of disconnecting some types of fixed connectors requires actual distortion of the terminal link. It is obvious that such a process would have many disadvantages where space is a limiting factor for a complete gun installation, and when the deformation required might result in permanent damage to the terminal link or the chute generally.

An object of this invention is to provide terminal links for an ammunition chute whereby the chute can be quickly and easily connected to and disconnected from associated apparatus or equipment without deformation of said links or the chute structure.

It is another object to provide such terminal members whereby the connection and disconnection of the chute can be made with the least possible movement of the chute to and from its place of connection.

It is an additional object to provide terminal links for an ammunition chute that are structurally rigid so as to retain the shape of the end openings of the chute under severe service conditions involving frequently repeated connections and disconnections, and to provide such terminal links with retractile connectors whereby the links can be disconnected from their place of attachment with a minimum of movement of the links and the chute.

The invention and its objects will be better understood from the following description considered in connection with the accompanying

2

drawings. It is to be expressly understood, however, that the drawings are for the purpose of illustration and description only and are not intended as a definition of the limits of the invention.

Fig. 1 is a view of the invention showing the terminal link attached to one end of an ammunition chute, and connected to an ammunition box by retractile connectors and associated alignment members.

Fig. 2 is a projection of Fig. 1 showing an opening outlined by the link through which ammunition passes.

Fig. 3 is an end view of the terminal link showing a connector retracted from engagement with an associated member as shown on the left of Fig. 1.

Fig. 4 is a section taken on line 4—4 of Fig. 2 showing detailed construction of the connector.

Fig. 5 is a fragmentary view partly in section showing the terminal link attached to the other end of an ammunition chute which is opposite to that shown in Fig. 1.

Referring to Fig. 1, a flexible feed chute, for guiding ammunition assembled in belt formation, is shown by dotted lines, and is indicated generally by reference numeral 10. The foresaid United States Patents 2,477,264, issued July 26, 1949, and 2,419,315, issued April 22, 1947, both of which were assigned to Hughes Tool Company, of Houston, Texas, clearly describe the feed chute 10, and said patents are hereby made a part of this disclosure, with particular reference to the constructional details of the means for linking together the transverse elements forming the chute and linking of the end transverse element to a terminal member.

In the present invention, the terminal link, indicated generally by reference numeral 12, includes two elongated horizontal members 14 and 16 having at their extreme ends vertical legs 14', 14'', 16' and 16'', and shaped for assembly opposite each other so as to form a unitary oblong structure having a transverse passageway 18 which conforms to the cross sectional configuration of the passageway existing in an attached ammunition chute 10.

Mounted on each end of link 12 is a retractile connector 20, which includes a guide element 22 for a slidble bolt 24 mounted in a slidble manner within the guide element 22. A latch 26, pivoted on bolt 24 by means of pin 28, is provided with a hook 30 formed on one end so as to face the bolt, and on the other end with a finger grip 32 for manual operation of the lever. A leaf spring

34 (Fig. 4), normally urging the hook toward the bolt is interposed between the bolt and the finger grip side of the latch.

A stop 36 (Figs. 1 and 4), projecting from the guide element 22, serves to limit the travel of the bolt by engaging the hook 30 in one direction of travel as shown in Fig. 3 and on the left of Fig. 1, and by engaging the pin 28 in the other direction of travel as shown in Fig. 4 and on the right of Fig. 1.

The end view of the terminal link 12 (Fig. 3), illustrates a plan view of connector 20 in its relationship with respect to a socket member 38 which has a hollow cross section similar to guide element 22 so that bolt 24 can enter and slide freely in the passageway 39 provided by the hollow cross section. In Fig. 3, the bolt 24 has been moved to the right until hook 30 engaged stop 36, and its position is similar to that shown on the left side of Fig. 1. It is to be noted that a portion 25 of bolt 24 remains in engagement with socket member 38 to provide a means for initial alignment so that chute 16 can be easily connected to an apparatus such as a gun or ammunition box, etc. The exact length of portion 25 determines the distance the link 12 must be moved to completely break the connection between it and the associated apparatus. The length of portion 25 is such that a connection and a disconnection of the link and its attached chute can be made substantially without moving the link and chute combination, and without distorting either the link or the chute. Thus, the particular configuration into which the chute was formed remains, even though repeated connections and disconnections are required.

In Fig. 4 the bolt 24 has been moved toward the left until pin 28 engaged stop 36, and, in this position, which is similar to that shown on the right side of Fig. 1, bolt 24 has entered the passageway 39 of socket member 38 a sufficient distance to receive adequate support and to allow the hook 30 of latching lever 26, urged by spring 34, to drop behind bar 40 of member 38. Bar 40, an integral part of member 38 is formed by removing a section of wall that defines passageway 39.

To connect a completely assembled link 12, with its attached chute 16 as shown in Fig. 1, to an apparatus such as ammunition box 41, bolt 24 of each retractile connector 20 is withdrawn until the hook 30 strikes the stop 36, as shown on the left side of Fig. 1, leaving portion 25 extending beyond the body element 22.

The link is aligned with an opening in the box 41 by inserting portions 25 of each bolt 24 into passageway 39 of its respective socket member 38. Each bolt is then moved into its aligned passageway 39 until the hook 30 drops behind the bar 40, thereby completing the connection by latching the feed chute 16 in position.

Pressure on the latching lever 26 at the finger grip 32 in a direction to overcome the spring 34 will lift the hook from behind bar 40 and permit withdrawal of bolt 24 from the passageway 39 to complete the disconnection. Thereafter, a slight backward movement of the link will withdraw portion 25 of bolt 24 from socket member 38 to free link 12 from the associated apparatus completely.

It is to be noted, that movement of latch 26, in a direction opposing the force of spring 34, is limited by the latch flanges 31 striking bolt 24, as best shown on the left in Fig. 1, and in Fig. 4. Such limited movement of latch 26 insures the engagement of hook 30 with stop 36, which pre-

vents complete withdrawal of bolt 24 from guide 22 of the retractile connector 20.

In order to provide a rigid light weight structure for link 12, elongated members 14 and 16 are made of relatively thin material, and are provided with channel shaped cross sections having flanges extending in a direction across the passageway 18. Extending from flanges 36 and 37 which face chute 16, and bent crosswise of members 14 and 16, are hooks 13, 13', 15, and 15' which have a spaced relationship, and a size and shape for attachment, by means of links 11 and 11', to the particular end of ammunition chute 16, shown in Fig. 1.

Guide members 17, 17', 19, and 19' extend through passageway 18 from flanges 45 and 47 provided on members 14 and 16. Said guide members are of sufficient length and width to overlap the hooks 13, 13', 15, and 15'. This overlap serves to guide ammunition 50 over said hooks, and to prevent accidental disengagement from links 11 and 11'.

From one edge of vertical legs 14' and 16', hooks 21 and 23 are bent inwardly to form means for attachment to links 33 and 33' of ammunition chute 16. From the opposite edge of vertical legs 14' and 16', guides 27 and 29 are formed so as to overlap the hooks 21 and 23. This overlap serves to guide ammunition over hooks 21 and 23, as well as to prevent their accidental disengagement from links 33 and 33'.

A terminal link 12', shown in Fig. 5, is similar to terminal link 12, Figs. 1, 2, 3, and 4, except for the modifications necessary for the attachment of link 12' to the other end of feed chute 16. Guide members 53 and 55, extending from opposing flanges of elongated members 52 and 54, are bent in the same direction so as to extend through the passageway formed by assembling said members 52, 54 into a unitary structure 12'. The guide 52, partly broken away, is shown directly above guide 55. Both guide members 53 and 55 are shown attached to chute 16 by means of links 53' and 55' located at the end of its respective guide member, which links engage hooks, such as hook 58, provided for that purpose on feed chute 16.

Link 57, formed as part of vertical leg 52'', engages hook 58, provided for that purpose on feed chute 16. A guide 59, mounted as shown in Fig. 5, covers the hole in link 57 and prevents any possibility of interference with the movement of ammunition which might occur if the nose of a shell entered the hole. It is to be understood from Fig. 5 that the other end of link 12, while it is not shown, is constructed so as to be attached to feed chute 16 in the same manner as shown. It is to be further understood that terminal link 12' is to be provided with a complete retractile connector 20 on each end similar to link 12 in Figs. 1 and 2.

Various modifications and changes in the structure of the invention herein described and illustrated can be made by those skilled in the art without departing from the spirit of the appended claims.

What is claimed as new is:

1. In an ammunition guiding system of the type comprising a flexible feed chute having a plurality of transverse units interconnected by links and having a first transverse passageway therethrough, apparatus having an opening for receiving and for discharging ammunition, and a hollow socket means associated with the apparatus for aligning the first passageway with the opening in the apparatus; a terminal link comprising an oblong frame structure having a sec-

ond transverse passageway which conforms to the cross-sectional configuration of the first passageway in the feed chute, attachment hooks integral with and extending from said frame structure for attaching said terminal link to the links on the feed chute, and guide members integral with and extending from said frame structure and having a length and width to overlap said hooks thereby guiding the ammunition over said hooks and preventing accidental disengagement of the links from said hooks; and connectors mounted on said frame structure, each comprising a guide element, a bolt slidably mounted within said guide element to enter and slide freely within the hollow socket means, a latch pivoted intermediate its ends on said bolt, and a leaf spring disposed between said bolt and one end of said latch to urge the other end of said latch toward said bolt.

2. The terminal link defined in claim 1 where-
in said guide element has four surfaces provid-
ing a rectangular cross-section longitudinally
and transversely and has a portion of one of said
surfaces cut away thereby leaving a narrow seg-
ment of said one of said surfaces, and a stop pro-
15
20
25

jecting from and integral with said segment of
said one of said surfaces; wherein said bolt has
three surfaces providing a substantially U-shape
cross-section, parallel leaves integral with said
bolt and extending from two of said surfaces,
each of said leaves having an orifice, and a pin
extending through said orifices and providing a
pivot for said latch; and wherein a hook is formed
on one of the ends of said latch, said hook facing
said bolt, and a finger grip formed on the other
end of said latch for manually depressing said
other end of said latch against the action of said
leaf spring and for manually protracting and re-
tracting said latch.
